[57] CLAIM

The ornamental design for a rotating warning beacon, as shown and described.

DESCRIPTION

FIG. 1 is a front elevational view of a rotating warning beacon showing our new design, the rear being a mirror image;

FIG. 2 is a bottom plan view thereof;

FIG. 3 is a side elevational view thereof, the opposite side being a mirror image; and,

FIG. 4 is a top plan view thereof.

The ribbing around the perimeter of the housing is fragmentarily shown in FIGS. 2 and 4 for convenience of illustration, it being understood that the ribbing is continuous as indicated in FIGS. 1 and 3.

FIG. 1

FIG. 2

FIG. 3

FIG. 4
